THREE ROLL WRINGER

Nicholas L. Etten, Waterloo, Iowa

Application September 29, 1938, Serial No. 232,377

26 Claims. (Cl. 68—253)

My present invention relates to clothes wringers and more particularly to wringers of such design and construction that the work is first fed between a pair of rolls under reduced pressure and secondarily fed between rolls cooperating under normal operating pressure.

In the prior art certain attempts have been made to provide a multiple roll wringer of such design that the rolls on the feed side of the machine operate under sufficiently reduced pressure as to eliminate any possibility of injury to the operator in the event that her hand should come between the rolls.

As heretofore constructed, however, these wringers have been subject to numerous objections and criticisms and have never become practically successful, since they have ordinarily been of such complicated design that they are both expensive to build and cumbersome in operation. It is, therefore, a principal object of this invention to provide a wringer having wringing rolls operating under normal pressure and feed rolls operating under reduced pressure wherein the general design, appearance and mode of operation closely resembles the conventional type of two-roll wringer.

A further object of this invention is to provide a multiple roll wringer of symmetrical design such that all the visible parts are identical on the feed and discharge sides of the machine, in order that the arrangement of parts and mode of operation will be identical whether the machine is being operated in forward or reverse direction.

Another object is to provide a multiple roll wringer of such design that all adjustments necessary to adapt the machine for reverse operation may be simultaneously accomplished by the operation of a single manually operable reversing lever.

Another important object of the invention is to provide a multiple roll wringer including wringing rolls and feed rolls adapted to operate under reduced pressure wherein the work may be fed into the wringer at an angle convenient to the operator and wherein the work will leave the wringer at such an angle as to insure falling in its proper position from the side of the wringer opposite the operator.

Another important object of the invention is to provide a multiple roll wringer wherein the rolls maintain their relative positions at all times, but wherein the operating pressure relationship existing between the rolls may be altered to adapt the machine for forward and reverse operation.

Another object of the invention is to provide

a multiple roll wringer having wringing rolls and reduced pressure feed rolls, with a feed roll tensioning mechanism of such design and construction that the feed rolls operate at maximum pressure when the rolls are in contact and at reduced pressure whenever the rolls are moved into spaced relationship.

A further object is to provide a multiple roll wringer which is simple in design, rugged in construction and economical in manufacture.

Referring now more particularly to the drawings in which a preferred embodiment of the present invention has been illustrated:

Fig. 1 is a longitudinal sectional view of a wringer constructed in accordance with the principles of this invention;

Fig. 2 is a side elevation of the wringer in its released position, certain parts having been broken away to more clearly illustrate the operating mechanisms;

Fig. 3 is a transverse sectional view taken substantially on the plane of the line 3—3 of Fig. 1;

Fig. 4 is a transverse sectional view taken substantially on the plane of the line 4—4 of Fig. 1;

Fig. 5 is a transverse sectional view taken substantially on the plane of the line 5—5 of Fig. 1;

Fig. 6 is a fragmentary plan view of the pressure shifting mechanism, being taken substantially on the plane of the line 6—6 of Fig. 5;

Fig. 7 is a detail plan sectional view of the bearings and slideways at one end of the rolls and is taken substantially on the plane of the line 7—7 of Fig. 1;

Fig. 8 is a detail plan sectional view of the bearings and slideways at the opposite end of the wringer rolls and is taken substantially on the plane of the line 8—8 of Fig. 1;

Fig. 9 is a diagrammatic view of the wringer rolls in one of their normal positions; and

Fig. 10 is a diagrammatic view similar to Fig. 9, showing an emergency position of the rolls.

The entire wringer structure here illustrated is preferably mounted on and supported by a power head 11 having a lower flanged portion 12 adapted to be carried by and to make driving connection with any conventional vertical wringer drive shaft, such as is customarily provided on modern washing machines. The entire wringer frame is secured to the power head 11 by means of a bracket 13 secured to the spaced flanges 14 of the power head 11 by a plurality of machine screws 15. The bracket 13 in turn supports a vertical bearing housing or slideway 16 which may be secured to the bracket 13 in any

suitable manner, as, for example, by spot welding or by means of a plurality of rivets 17.

A pair of longitudinally extending bottom channel members 18 and 19 are secured to the lower end of the bearing housing 16 and extend horizontally to the outer end of the wringer where they are secured to and support a vertically extending outer bearing housing 21. The longitudinally extending bottom channels 18 and 19 are rigidly secured to the bearing housings 16 and 21 by spot welding or in any of the other means customarily used in the art in such a manner that these parts combine to provide a rigid U-shaped wringer frame including vertical bearing housings at each of its ends.

The wringer rolls extend between the bearing housings 16 and 21 and are journaled in suitable bearing heads mounted within these housings and will hereinafter be described. In the construction illustrated there are three of these rolls and the arrangement is such that the top roll 25 (which is, incidentally, the power driven roll) will operate against both of the two lower rolls 26 and 27, but the two lower rolls 26 and 27 are so mounted as to maintain a slight spaced relationship with respect to each other at all times. The top roll 25 is axially stationary during the operation of the wringer and is driven by means of a spur gear 28 carried on the power head 11 which is adapted to mesh with the gear 29 secured to the extreme end of the upper roll shaft 31.

At the inner end of the upper roll 25, the roll shaft 31 is journaled in a vertically slidable bearing block 32 housed in a bearing slideway 33 and secured therein by means of the inwardly extending flanges 34, which seat in the grooves 35 in the bearing block 32. The bearing slideway 33 is mounted on a plate 36 by means of a plurality of machine screws 37, and the plate 36 is in turn secured within the bearing housing 16 by welding.

At the outer end of the upper roll 25 the roll shaft 31 is journaled for rotation in a vertically movable bearing member 41 mounted within a bearing slideway 42, which may be welded or otherwise secured to the bearing housing 21.

In the preferred design of the invention here illustrated, a typical wringer roll mechanism has been included whereby the operator may manually trip external control means in order to release the upper roll 25 from all pressure relationship with the lower rolls 26 and 27 in a manner well-known in the art. It should be pointed out that with the improved design and construction of the present wringer, such a release mechanism is not ordinarily required, since it is believed to be a practical impossibility for the operator to become injured by the machine, but it has been included in the preferred design here illustrated as an additional safeguard.

In view of these facts it is believed unnecessary to describe the wringer release mechanism in complete detail, it being believed sufficient to point out that the entire top frame member 51 may be released from the frame members 16, 18, 19 and 21, by manually depressing the release knob 52. This will cause the latch 53 to disengage the latch pin 54, affixed to the power head 11, and since the top frame member 51 normally limits the upward movement of the upper wringer roll bearings 32 and 41, the act of releasing the top frame 51 will be effective to completely release the upper roll 25 from any pres-

sure engagement with either of the lower rolls 26 or 27.

After such release has taken place, the mechanism may be reset by reengaging the latch 53 with the latch pin 54 and thereafter swinging the resetting lever 55 arcuately downwardly around the pivot 56, in order that the compression link 57 extending between the ears 58 on the bearing housing 21 and ears 59 on the resetting lever 55 will be effective to draw the entire top structure downwardly into operating position. At that time the adjusting screw 45 will come to bear against the top surface of the bearing 32 and move it downwardly into operating position, and the plate 46 will similarly bear against the top surface of the bearing 41 and move it downwardly into its proper operating position. This pressure release and reset mechanism is set forth and claimed more in detail in my prior patent on Wringer, No. 2,232,378, granted February 18, 1941.

From the above it will be seen that in the normal operation of the wringer the upper roll 25 is journaled between stationary bearings 32 and 41 and is driven from the power head 11 through the medium of the gears 28 and 29. The lower rolls 26 and 27 are resiliently urged upwardly against the roll 25 to provide proper wringing action for the work passing between the rolls. The rolls 26 and 27 are journaled for rotation in bearing members 61 carried in the respective opposite ends of a traverse bearing plate 62 at the outer end of the rolls and an identical traverse bearing plate 63 at the inner end of the rolls (see Figs. 4, 9 and 10). Each of the bearing plates 62 and 63 is free for vertical movement in the bearing housings 21 and 16, respectively, and each is supported by rollers 64 and 65 at the upper end of a pair of tension shifting arms 66 and 67 stationarily secured on either end of a tension rocker shaft 68 by means of the cross pins 69. The rocker shaft 68 is urged bodily upwardly by a leaf spring 71 anchored at its mid-point to an adjusting screw 72 carried by a bracket 73 extending between the spaced longitudinal frame members 18 and 19.

The arrangement is such that each end of the leaf spring 71 bears upwardly against the rocker shaft 68 and forces each of the bearing plates 62 and 63 upwardly by means of the connection established by the rollers 64 and 65 and the shifting arms 66 and 67. A space between the longitudinally extending channel members 18 and 19 serves to define a housing preventing the displacement of the spring 71 and a pair of slots 74 and 75 are provided in the bearing housing 21 and in the plate 36, respectively, to accommodate the hub portions of the shifting levers 66 and 67 and define a vertical path of movement for the rocker shaft 68.

It will be seen from an examination of Fig. 1 that the lower rolls 26 and 27 are maintained in proper transverse relation by means of a plurality of spacers 76, which spacers also hold the bearing plates 62 and 63 against axial movement so that said plates will at all times be engaged by the rollers 64 and 65 on the arms 66 and 67. An arcuate roller track 77 (Figs. 4 and 9) is provided on each of the bearing plates 62 and 63 in order that the rollers 64 and 65 may move from their position at one end of the track 77 indicated at 77a, to a position at the opposite end, indicated at 77b. As hereinbefore pointed out, the entire operating pressure of the wringer as exerted by the spring 71 acts to force the rocker shaft 68 upwardly and consequently to exert an upward force

on the bearing plates 62 and 63 in such a manner as to force the lower rolls 26 and 27 into operating engagement with the upper roll 25.

It is an object of this invention, however, to provide a construction in which the operating pressure effective between each pair of rolls is so controlled that the work being fed through the wringer will first pass between a pair of rolls operating at a very reduced pressure which will be incapable of causing any injury to the operator in the event that her hands should come between the rolls, and will then pass between a pair of rolls exerting the normal pressure required for efficient wringing. This feature of the device will be readily understood by reference to Figs. 9 and 10, illustrating the various parts in different positions of operation.

Fig. 9 shows the normal operating position of the machine when the rolls are rotating in the direction indicated by the arrows. At this time it will be noted that the operator feeds the work into the machine at the left hand side where it passes between the rolls 25 and 27. After the work has passed between the rolls 25 and 27 it is engaged by the roll 26 and the wringing action is completed as the work passes between the wringing rolls 25 and 26.

In this connection it should be noted that the rolls are so positioned as to afford a convenient angle of feed for the operator and the work leaves the machine at such an angle that it will freely fall into any receptacle such as is customarily provided without danger of wrapping around any of the several rolls or falling on the feed side of the machine. It should also be noticed that the feeding of the work between the several rolls is accomplished without the use of any auxiliary flanges, plates or other guiding means which may serve to entangle or tear the clothes. It will be appreciated that when the work is fed between the rollers 25 and 27, it is not only prevented from moving downwardly between the rolls 26 and 27 by the limited space between the rolls 26 and 27, but is also carried upwardly into its proper path between the rolls 25 and 26 by the rotation of the roll 26.

At this time the pressure shifting arms 66 and 67 are positioned at the point 77a, and the force exerted by the spring 71 will act upwardly along the center line of the tension shifting arms 66 and 67, as indicated by the direction arrow 111, to force the rolls 26 and 27 into engagement with the roll 25. When the rolls are in this position, however, the roll 27 will operate under greatly reduced pressure, since the leverage tending to move it into engagement with the roll 25 is of negative mechanical advantage, as will be described more fully hereinafter. It is desirable, however, that even this light pressure effective between the rolls 25 and 27 shall be further reduced in the event that the operator's hand should come between the rolls. It is, of course, perhaps desirable that in the event the operator's hand should come between the rolls that sufficient pinching action shall take place to result in an involuntary withdrawal of her hand, but in the customary construction it has been found almost impossible to provide a tension sufficient to cause involuntary or reflex action and yet insufficient to grip the hand and prevent it from being withdrawn from the grip of the rolls.

In the present device this problem has been satisfactorily solved since the rolls 25 and 27 are operating under maximum pressure when they are in contact; but when separated, as illustrated

in Fig. 10, the operating pressure is further reduced as the spaced relationship between the rolls increases. Thus, as any object comes between the rolls and forces them into spaced apart relation, as illustrated in Fig. 10, the operating plates 62 and 63 pivot downwardly about the axis of the roll 26 in such a manner that the mechanical advantage of the leverage is reduced and the operating pressure is diminished accordingly.

When the operator desires to reverse the wringer and feed the clothes from the opposite direction, it is, of course, necessary not only to reverse the direction of rotation of the rolls but to alter the existing pressure relationship in such a manner that the rolls 25 and 27 operate under the full wringing pressure, while the rolls 25 and 26 now operate as feed rolls under reduced pressure. To accomplish this the rock shaft 68 is partially rotated to swing the tension spring arms 66 and 67 from the solid line position illustrated in Fig. 9 to the dotted line position in such a manner that the rollers 64 and 65 will be moved from the position 77a to the position 77b. The pressure relationship existing between the rolls will now be the exact reverse of that heretofore described, but will operate in exactly the same manner, as the clothes pass through the machine from right to left.

It is quite important, of course, that the pressure relationships shall be changed automatically whenever the direction of rotation of the rolls is reversed and to this end a linkage has been provided whereby the operation of the reversing handle 81 carried on the power head 11 will serve to rock the rocker shaft 68 as heretofore described. To accomplish this result a crank arm 82 is provided on the shaft 83 of the reversing lever 81 and this crank is operatively connected to an offset arm 85 by a connecting rod 84. This offset arm 85 extends between a stub shaft 86 journaled in a bearing 87 secured to one of the flanges 14 of the power head 11, and a longitudinal coaxial pivot stud 88 mounted in a boss portion 89 of the power head 11 (Fig. 6). By moving the reversing handle 81 through 180° of movement, as required to reverse the direction of rotation of the rolls, the crank 82, connecting rod 84 and offset arm 85 will move from the solid line position illustrated in Fig. 5 to the dotted line position there shown and will be effective to rotate the stub shaft 86 and the forked shifting yoke 91 carried thereby through predetermined arcuate movement. A roller 92 is mounted on a downwardly extending arm 93 carried by the shifting arm 67 and this roller 92 extends into a notched portion 90 of the arm 91 to establish an operating connection whereby the partial rotation of the stub shaft 86 will serve to rock the rocker shaft 68 and thus move the rollers 64 and 65 from the position 77a to the position 77b. It will be clear that the connection established between the arm 91 and roller 92 will permit the rock shaft 68 to move downwardly against the pressure of the spring 71 at all times when work of considerable thickness is being passed between the wringer rolls, but that this connection will maintain the rocker shaft 68 and the arms 66 and 67 in their proper predetermined angular position irrespective of the vertical movement of these elements.

When the wringer is reversed in order that the work be fed into the machine from the opposite side, it is desirable that some means be provided for directing the flow of drain water in such a manner that all water removed from the work

will drain toward the feed side of the machine, rather than toward the delivery side. In the present construction this desirable result has been accomplished by providing a corrugated water deflector or flipper 94 mounted below the wringer rolls and between the bearing housings 16 and 21 by means of a floating suspension comprising four tension springs 95 which extend inwardly from the flanges of the bearing housings 16 and 21 to suitable studs or rivets 96 in the vertical end flanges 97 of the water deflector 94. These tension springs 95 cooperate to resiliently support the water deflector 94 and permit pivotal movement of the deflector about the axis of the rivets 96 (see Fig. 3). In order that the deflector 94 may be automatically moved from one of its positions to the other when the direction of rotation of the rolls is changed, a pair of upwardly extending pins 98 are positioned in suitable transverse drilled openings in the rocker shaft 68 in such a manner that they will extend upwardly and seat between a pair of downwardly extending flanges 99 on brackets 101 welded or otherwise secured to the lower surface of the water deflector 94. The pins 98 are of sufficient length as to tend to raise the water deflector 94 to a sufficient height that the axis of the rivets 96 is above the normal line of the tension springs 95. This causes the tension springs 95 to exert a slight downward pressure which is sufficient to prevent any unnecessary movement of the water deflector 95, but insufficient to interfere with the rocking motion of the rocker shaft 68. When the operator reverses the wringer by movement of the reversing handle 81, it will be clear that the rocking movement imparted to the shaft 68 will cause the pins 98 to move in a counterclockwise direction, as viewed in Fig. 3, and that as these pins pass the vertical position they will cross the center line between the shaft 68 and the rivets 96 and will shift the water deflector in a clockwise direction in such a manner as to reverse the flow of water.

Fig. 9 is used to diagrammatically represent the operating forces effective on the several rolls during the normal operation of the wringer. It will, of course, be understood that the force exerted by the leaf spring 71 will act between the upper roll 25 and the rocker shaft 68. However, when the shifting arms 66 and 67 are in the full line position, this force will be transmitted angularly upwardly against the bearing plates 62 and 63. The direction of force and its magnitude are indicated by the angular direction and the length of the arrow 111, respectively. Since the roll 26 is not free to move, being restricted in its upper movement by the roll 25 and in its lateral movement by the bearing housings 16 and 21, the bearing plates 62 and 63 will act as levers pivoted upon a fulcrum concentric with the roll 26 and will exert a reduced upward pressure upon the roll 27, the magnitude of which is variable in accordance with the position of the several parts.

In the normal position shown in Fig. 9, the angular force represented by the arrow 111 will be resolved into a vertical component represented by the arrow 112 and the horizontal component represented by the arrow 113. The horizontal force 113 will serve only to hold the bearing plates 62 and 63 against the side walls of the bearing housings, but the vertical component 112 will tend to pivot the bearing plates 62 and 63 in a clockwise direction about the axis of the roll 26 and thus force the roll 27 upwardly into contact with the roll 25 with the force, the direction and

magnitude of which are indicated by the arrow 114.

As heretofore pointed out, it is desirable that this force 114 be very much reduced as compared with the force 112 acting upon the roll 26. This is accomplished in the present construction, since the effective length of lever at which the force 112 acts is represented by the character L and the effective length of the lever at which the force 114 acts is represented by l. It will be seen then that the difference in effective lever lengths causes the spring 71 to act on the rolls 26 and 27 under different degrees of mechanical advantage, and results in accomplishing the desired differential pressure relationship between the several rolls. The operator may now feed the work from left to right through the wringer in such a manner that the clothes will pass first between the rolls 25 and 27, where they will be subjected to a relatively light wringing action and then between the rolls 25 and 26 where the final wringing operation will take place under full pressure.

In the event that the operator should accidentally allow her hands to come between the rolls 25 and 27, the force 114 will be sufficient to cause a definite pinching which will result in an involuntary withdrawal of the hand, but which is insufficient to cause any permanent or serious injury. In this connection it should also be pointed out that unlike ordinary wringer constructions the operating pressure between the feed rolls 25 and 27 does not become greater as the rolls are forced apart, but on the contrary becomes less whenever any article of considerable thickness comes between the rolls.

The principal advantage gained by this construction is that in the event that the operator should become caught between the rolls, the operating pressure will be immediately reduced to zero or to such a low magnitude that there is no possibility of the gripping action of the rolls preventing immediate removal of the operator's hand. This operation will be more readily understood by reference to Fig. 10, which is a diagrammatic view similar to Fig. 9, showing the several rolls in emergency position. In the event that a finger 115 should come between the rolls 25 and 27, it will, of course, separate the rolls 25 and 27 until they assume the positions here indicated. When the roll 27 moves downwardly the bearing plates 62 and 63 pivot about the fulcrum defined by the axis of the roll 26 and the rock 68 will be forced slightly downwardly by the shifting arms 66 and 67 to slightly compress the leaf spring 71. The vertical movement of the rock shaft 68, as indicated by the dimension lines 116, and the corresponding compression of the spring 71, will cause the upward force acting upon the bearing plates 62 and 63 to become slightly greater than before. This force, however, now acts upwardly at a slightly different angle, as indicated by the arrow 117. The arrows 118 and 119 indicate the vertical and horizontal components of the force 117. These forces are also greater than before, but exert less upward force upon the roll 27, since the angular relationship of the several parts has been so altered that the effective length of the lever L has now been reduced to the length L', while the effective length of the lever l remains constant as indicated by l'. Since the lever lengths L' and l' have now become so greatly disproportionate, it will be seen that although the original force exerted by the spring 71 is greater, as indicated at

117, the upward force effective on the roll 27 has been reduced to a magnitude indicated by the length of the arrow 121.

The dimensions and angular relationship existing between the several rolls and linkages are indicated in the drawings in their present preferred proportions, which are believed to be the most satisfactory for ordinary applications. It will be understood, however, that the directions and magnitudes of the several forces herein mentioned may be varied at will by alterations of the dimensions of the several parts, if it is found desirable to do so.

While it is believed that the operation of the machine will be readily understood from the foregoing description, it will nevertheless be here briefly reviewed.

Before beginning to feed clothes to the machine, the operator will move the power head reversing handle 81 in either direction from the vertical position shown to engage the gear mechanisms within the power head 11 and drive the rolls 25, 26 and 27 either in their forward or reverse direction. When the handle 81 is moved, the connecting rod 84 extending downwardly from the crank arm 83 affixed thereto will operate through the offset link 85 and stub shaft 86 to move the shifting arm 91 into one of its proper operating positions. The shifting yoke 91, of course, will act upon the roller 92 carried by the arm 93 in order to rock the rock shaft 68, as well as the bearing support arms 66 and 67 into one of their operating positions.

The movement of the rock shaft 68 will not only be effective to swing the arms 66 and 67 into their proper positions, but will also cause the vertical pins 98 to shift the water deflector 94 into a position corresponding with the direction of feed established by the direction of rotation of the rolls.

The clothes may now be fed into the machine by the operator without the necessity of any further adjustments and it will be noticed that the rolls are so positioned as to provide a convenient angle of feed for introducing the work into the machine and the proper angle of discharge for the work leaving the machine, so that there will be no inconvenience to the operator, nor any possibility of work winding around the rolls or being discharged from the wrong side of the wringer, or in such a manner that it might fall among the wet clothes.

In this connection it should be pointed out that the operation of the improved wringer I disclose is exactly the same from the viewpoint of the operator as is the operation of any one of the several conventional wringers now in use. From a practical aspect this is a fact of some importance since it is unnecessary to instruct an operator in the use of the wringer or to overcome any hesitancy about accepting an unfamiliar mechanism. As the operator feeds the clothes into the machine she has full access to the feed rolls over a large portion of their circumference and is thus enabled to feed work into the wringer rapidly and positively. At the same time all danger of becoming injured by the rolls has been eliminated since the instant the feed rolls separate the operating pressure is reduced practically to zero and the hand may be withdrawn without injury.

To reverse the operation of the wringer, the lever 81 will be moved to its other position which will result in shifting the existing pressure relationships of the several parts, reversing the direction of movement of the rolls and shifting the

water deflector to reverse the direction of flow of the drain water.

The wringer will now operate in the reverse direction, but otherwise the operation will be exactly as heretofore described. In this connection it should be pointed out that the principles of this invention permit the construction of a wringer embodying these advantages in a symmetrical form; that is, with both the feed side and the discharge side of the wringer identical in construction. Since public demand requires that commercial wringers be capable of reverse operation, it is very important that this may be accomplished by merely altering the tension relationship existing between the several rolls, rather than by shifting the rolls in their relative positions with respect to each other. The reason for this will be readily appreciated when it is realized that this feature permits an identical mode of operation of the mechanism in both directions of feed, and requires no adjustments for reversing the operation other than the operation of the customary gear reverse lever. This construction also permits the wringer frame to be of small and simple design, such that the wringer will be readily accepted by the public, and such that it may be economically manufactured.

While I have shown and described one embodiment of the invention for purposes of illustration, as required by the patent statutes, it is nevertheless subject to numerous modifications and variations without departing from the inventive spirit, and I, therefore, do not wish to be limited except as by the scope of the appended claims.

I claim:

1. In a multiple roll wringer, the combination of a pair of wringer rolls, movable supporting members whereby said pair of wringer rolls are maintained in predetermined spaced relationship with respect to each other, a third roll common to both rolls of said aforementioned pair of rolls and adapted to simultaneously bear against each roll of the pair of rolls under an operating pressure of predetermined and adjustable magnitude, a spring below the pair of rolls acting directly thereon common to all of the rolls and being the sole resilient pressure applying means between all of the rolls whereby said pair of rolls are urged into cooperating pressure relationship with the third roll, means to unequally divide the pressure exerted by the pressure spring and cause the said pair of rolls to bear against the common roll under unequal pressure relationships, and manually operable control means effective to alter the magnitude of the operating pressures effective between the several rolls.

2. In a multiple roll wringer, the combination of a pair of wringer rolls, movable supporting members whereby said pair of wringer rolls are maintained in predetermined spaced relationship with respect to each other, a third roll common to each roll of said aforementioned pair of rolls and adapted to simultaneously bear against each roll of the pair of rolls under an operating pressure of predetermined and adjustable magnitude, a spring below the pair of rolls acting directly thereon common to all of the rolls and being the sole resilient pressure applying means between all of the rolls whereby said pair of rolls are urged into cooperating pressure relationship with the third roll, and means to unequally divide the pressure exerted by said pressure spring and cause the said pair of rolls to bear against the common roll under unequal pressure relationships.

3. In a multiple roll wringer, the combination of a pair of wringer rolls, movable supporting members whereby said pair of wringer rolls are maintained in predetermined spaced relationship with respect to each other, a third roll common to both rolls of said aforementioned pair of rolls and adapted to simultaneously bear against each roll of the pair of rolls under an operating pressure of predetermined and adjustable magnitude, a single means below the pair of rolls acting directly thereon common to all of the rolls and being the sole resilient pressure applying means between all of the rolls whereby said pair of rolls are urged into cooperating pressure relationship with the third roll, and means effective to cause the said pair of rolls to bear against the common roll under unequal pressure relationships.

4. In a wringer, a pair of wringer rolls each adapted to cooperatively engage a third roll, unitary spring means common to all rolls and adapted to urge each roll of said pair of rolls into engagement with said third roll under unequal pressure conditions, means for driving said rolls in forward or reverse directions, manual control means for selectively effecting said drive in either direction, and levers responsive to the operation of said manual control whereby either of said rolls may be alternatively caused to engage said third roll under relatively light pressure relationship.

5. In a multiple roll clothes wringer, a frame; three rolls supported by said frame and comprising two guide rolls mounted in the same horizontal plane and a common pressure roll adapted to simultaneously contact both of said guide rolls; each of said rolls having a single operating position prior to wringing relative to said frame; a single means to establish a clothes wringing pressure bite and an auxiliary light pressure intake bite between respective pairs of said rolls, cooperating mechanism to reverse the location of said bites with respect to the frame to permit feeding clothes through said wringer from either side, and a shift member to actuate said cooperating mechanism.

6. In a multiple roll clothes wringer, a frame; three rolls supported by said frame and comprising two guide rolls mounted in the same horizontal plane and a common pressure roll adapted to simultaneously contact both of said guide rolls, each of said rolls having a single operating position prior to wringing located to define a triangle symmetrically disposed equally on each side of a vertical center plane to present identical roll structures at the intake and discharge sides of the wringer; a single means to establish a clothes wringing pressure bite and an auxiliary light pressure intake bite between respective pairs of said rolls, cooperating mechanism to reverse the location of said bites with respect to the frame to permit feeding clothes through said wringer from either side, and a shift member to actuate said cooperating mechanism.

7. In a multiple roll clothes wringer, a frame, three rolls, each supported in a single operating position prior to wringing with respect to said frame, a single means to establish a clothes wringing pressure bite and an auxiliary light pressure intake bite between respective pairs of said rolls, cooperating mechanism to reverse the location of said bites with respect to the frame to permit feeding clothes through said wringer from either side, and a shift member to actuate said cooperating mechanism.

8. In a reversible three-roll wringer to which

clothes may be fed from either side, a frame, two guide rolls, means to mount said guide rolls with the axes thereof spaced at fixed distances from each other and in the same horizontal plane, a pressure roll mounted in fixed axial position and intermediate and above said guide rolls, said pressure roll being common to both of said guide rolls and adapted to simultaneously coat with each of said guide rolls during both forward and reverse operation to establish a single path of material feed for both forward and reverse operation, and a single spring pressure means for effecting one type of pressure on one of the guide rolls and a different pressure on the other of said guide rolls.

9. In a multiple roll wringer adapted for reverse operation whereby clothes may be fed to said wringer from either side, a frame; three rolls comprising a pressure roll and two guide rolls adapted to simultaneously contact said pressure roll to define a path of work feed through the wringer, each of said rolls having a single operating position prior to wringing whereby the forward and reverse paths of feed will be mutually co-extensive, a single means at a lower level than the guide rolls for applying pressure to said guide rolls, and means for varying the pressure applied to the respective guide rolls according to the direction of turning movement thereof.

10. In a multiple roll clothes wringer, a frame, three rolls, each supported by said frame in a single operating position prior to wringing and in symmetrical relationship with said frame to present identical roll structures at each side of said frame, said rolls comprising two rolls each adapted to contact a common roll to provide two pairs of feed rolls, a single means to establish a clothes wringing pressure bite and an auxiliary light pressure intake bite between respective pairs of said rolls, cooperating mechanism to reverse the location of said bites with respect to said pairs of rolls to permit feeding clothes in the opposite direction through said pairs of rolls, and a shift member to actuate said cooperating mechanism.

11. In a multiple roll clothes wringer, a frame, two guide rolls mounted in limited spaced relationship to each other, a third roll adapted to simultaneously contact each of said guide rolls to provide two pairs of feed rolls having a single operating position prior to wringing and disposed in symmetrical arrangement about the center plane of the wringer structure, a single means to establish a light pressure intake bite between the first pair of said rolls and a clothes wringing pressure bite between the second pair of said rolls, cooperating mechanism to reverse the location of said bites with respect to said rolls to establish a clothes wringing pressure bite between said first named pair of rolls and a light pressure intake bite between said second named pair of rolls to permit feeding clothes through said wringer from the other side, and a shift member to actuate said cooperating mechanism.

12. In a multiple roll wringer, the combination of a pair of wringer rolls, movable supporting members whereby said pair of wringer rolls are maintained in predetermined spaced relationship with respect to each other, a third roll common to both rolls of said aforementioned pair of rolls and adapted to simultaneously bear against each roll of the pair of rolls under an operating pressure of predetermined and adjustable magnitude, a spring common to all of the rolls and being the sole resilient pressure applying means between all

of the rolls whereby said rolls are caused to be in cooperating pressure relationship, means to unequally divide the pressure exerted by the pressure spring and cause the said pair of rolls to bear against the common roll under unequal pressure relationships, and manually operable control means effective to alter the magnitude of the operating pressures effective between the several rolls.

13. In a multiple roll wringer, the combination of a pair of wringer rolls, movable supporting members whereby said pair of wringer rolls are maintained in predetermined spaced relationship with respect to each other, a third roll common to each roll of said aforementioned pair of rolls and adapted to simultaneously bear against each roll of the pair of rolls under an operating pressure of predetermined and adjustable magnitude, a spring common to all of the rolls and being the sole resilient pressure applying means between all of the rolls whereby said rolls are caused to be in cooperating pressure relationship, and means to unequally divide the pressure exerted by said pressure spring and cause the said pair of rolls to bear against the common roll under unequal pressure relationships.

14. In a multiple roll wringer, the combination of a pair of wringer rolls, movable supporting members whereby said pair of wringer rolls are maintained in predetermined spaced relationship with respect to each other, a third roll common to both rolls of said aforementioned pair of rolls and adapted to simultaneously bear against each roll of the pair of rolls under an operating pressure of predetermined and adjustable magnitude, a single means common to all of the rolls and being the sole resilient pressure applying means between all of the rolls whereby said rolls are caused to be in cooperating pressure relationship, and means effective to cause the said pair of rolls to bear against the common roll under unequal pressure relationships.

15. A wringer comprising a frame, three rolls carried in said frame in position to establish a pair of roll bites, and a single pressure mechanism to simultaneously apply wringing pressure between two of said rolls at one roll bite and different and relatively lighter pressure between two of said rolls at the other roll bite and means to shift said pressure mechanism to reverse the relative location of said wringing bite and said light pressure bite with respect to said rolls.

16. In a wringer, a frame, a roll carried by said frame, a pair of rolls in said frame adapted to coact with said first roll to provide a pair of roll bites, a double journal at each end of said pair of rolls to maintain the same in fixed rotative position relative to each other, a single spring mechanism and means to apply the force of said spring mechanism against said journals between the axes of said pair of rolls to apply the major component between one of said pair of rolls and the first roll and the minor component between the other of said pair of rolls and the first roll to provide a heavy pressure bite and a light pressure bite respectively.

17. In a wringer, a frame, a roll carried by said frame, a pair of rolls in said frame adapted to coact with said first roll to provide a pair of roll bites, a double journal at each end of said rolls to maintain the same in fixed rotative position relative to each other, a single spring mechanism and means to apply the force of said spring mechanism against said journals between the axes of said pair of rolls to apply the major component

between one of said pair of rolls and the first roll and the minor component between the other of said pair of rolls and the first roll to provide a heavy pressure bite and a light pressure bite respectively and means to shift the application of said spring force to reverse the application of the major and minor components of said spring pressure.

18. A wringer comprising a frame, three rolls carried in said frame in position to establish a pair of roll bites, a single resilient pressure mechanism constituting the only resilient pressure mechanism of the wringer and operative at all times said wringer is conditioned for effective wringing operation to simultaneously apply wringing pressure between two of said rolls at one bite and different and relatively lighter pressure between two of said rolls at the other roll bite and manually operable mechanism to release said resilient pressure, said wringing and feeding rolls forming a wringing bite and a feeding bite in substantially a horizontal plane.

19. A wringer comprising a frame, a roll rotatably carried in said frame, a pair of rolls adjacent said first roll and a single means for alternately pressing one of said adjacent rolls against said first roll under resilient pressure to provide wringing rolls and to simultaneously press the other adjacent roll against one of said wringing rolls to provide rolls with a different and relatively lighter pressure for feeding material to said wringing rolls, said means constituting the sole resilient pressure means in said wringer, said unequal pressures being present at all times said wringer is conditioned for effective wringing operations, said wringing and feeding rolls forming a wringing bite and a feeding bite in substantially a horizontal plane.

20. A wringer comprising a frame, a roll rotatably carried in said frame, a pair of rolls adjacent said first roll, a single spring mechanism constituting the only spring mechanism of said wringer for applying resilient wringing pressure of one degree between one of said adjacent rolls and said first roll to provide wringing rolls and to simultaneously provide a resilient lighter pressure bite of less degree between the other adjacent roll and one of said wringing rolls to feed clothes to said wringing pressure bite, said unequal pressures being present at all times said wringer is conditioned for effective wringing operations and mechanism operable to release said spring mechanism to thereby release the pressure applied to said roll bites, said wringing and feeding rolls forming a wringing bite and a feeding bite in substantially a horizontal plane.

21. In a wringer, a roll tensioning mechanism whereby a pair of wringer rolls are urged into coacting relationship with a third roll common to each roll of said pair, said tensioning mechanism including a spring, facilities at each end of said rolls whereby the force exerted by said spring is caused to act upon said rolls, and means to provide unequal operating pressures on different rolls, including means associated with the spring-actuated facilities whereby either of the aforesaid pair of rolls may be caused to engage the common roll under a different pressure relationship, said last-mentioned means being responsive to relative lateral movement of one of said rolls for further reducing the effective operating pressure.

22. In a wringer, a roll tensioning mechanism whereby a pair of wringer rolls are urged into coacting relationship with a third roll common to each roll of said pair of rolls, said tensioning

mechanism including a spring, lever facilities at each end of said rolls whereby the force exerted by said spring is caused to act upon said rolls, and means providing unequal operating pressures on different rolls including means associated with the spring-actuated facilities whereby either of the aforesaid pair of rolls may be caused to engage the common roll under a different pressure relationship, said last-mentioned means being responsive to relative lateral movement of one of said rolls for further reducing the effective operating pressure.

23. In a wringer, a roll tensioning mechanism whereby a pair of wringer rolls are urged into coacting relationship with a third roll common to each roll of said pair of rolls, said tensioning mechanism including a spring, lever facilities at each end of said spring and adapted for movement about fulcrum points whereby the force exerted by said spring is caused to act upon said rolls, said lever facilities providing means for positioning the fulcrum points to cause unequal operating pressures on different rolls, including means associated with the spring-actuated facilities whereby either of the aforesaid pair of rolls may be caused to engage the common roll under a different pressure relationship, said last-mentioned means being responsive to relative lateral movement of one of said rolls operating under reduced pressure, for further reducing the effective operating pressure.

24. In a wringer, a roll tensioning mechanism whereby a pair of wringer rolls are urged into coacting relationship with a third roll common to each roll of said pair of rolls, said tensioning mechanism including a single spring extending longitudinally of said rolls, facilities including levers at each end of said spring and adapted for movement about fulcrum points whereby the force exerted by said spring is caused to act upon

said rolls, and means for positioning the fulcrum points for said levers to provide unequal operating pressures on different rolls, and including means associated with the spring-actuated facilities whereby either of the aforesaid pair of rolls may be caused to engage the common roll under a different pressure relationship, said last-mentioned means being responsive to relative lateral movement of one of said rolls operating under reduced pressure, for further reducing the effective operating pressure.

25. In a multiple roll clothes wringer, a frame; three rolls supported by said frame and comprising two guide rolls mounted in the same horizontal plane and a common pressure roll adapted to simultaneously contact both of said guide rolls; each of said rolls having a single operating position prior to wringing relative to said frame; a single means below the guide rolls and acting directly thereon to establish a clothes wringing pressure bite and an auxiliary light pressure intake bite between respective pairs of said rolls, cooperating mechanism to reverse the location of said bites with respect to the frame to permit feeding clothes through said wringer from either side, and a shift member to actuate said cooperating mechanism.

26. In a multiple roll clothes wringer, a frame, three rolls, each supported in a single operating position prior to wringing with respect to said frame, a single means below said rolls to establish a clothes wringing pressure bite and an auxiliary light pressure intake bite between respective pairs of said rolls, cooperating mechanism to reverse the location of said bites with respect to the frame to permit feeding clothes through said wringer from either side, and a shift member to actuate said cooperating mechanism.

NICHOLAS L. ETTEN.
